UNITED STATES PATENT OFFICE.

FREDERIC W. MACQUESTEN, OF EAST ORANGE, NEW JERSEY.

BUILDING-BLOCK.

966,226.

Specification of Letters Patent. Patented Aug. 2, 1910.

Application filed June 29, 1907. Serial No. 381,389.

To all whom it may concern:

Be it known that I, FREDERIC W. MACQUESTEN, a citizen of the United States, residing at East Orange, in the county of Essex and State of New Jersey, have invented certain Improvements in Building-Blocks, of which the following is a specification.

This invention relates to that class of building blocks which are formed or molded from cement, concrete or the like, and when dried or hardened are laid or joined together to form a wall. In this manner blocks of considerable size can be employed to facilitate the erection of the wall, and by making said blocks hollow great lightness is secured in the wall. It has, however, been a disadvantage of this kind of building construction, that the cement blocks do not readily lend themselves to architectural treatment or ornamentation of the wall; in other words, the wall has been severely plain, without any possibility of disguising its real formation of homely blocks.

The objects of this invention are to obtain a building block which shall better lend itself to architectural treatment or ornamentation of a building; to secure for this purpose a block provided at its face with inserts; to provide such inserts which shall be an integral part of the block from its time of molding; to conceal the lines of joining of different blocks; to enable blocks to be readily laid at equal distances apart without the loss of time or employment of skilled labor; to save labor and expense, and to obtain other advantages and results as may be brought out in the following description.

Referring to the accompanying drawings, in which like numerals of reference indicate corresponding parts in each of the several figures; Figure 1 is a face view of a portion of a wall composed of blocks of my improved construction; Fig. 2 is a perspective view of a single block by itself; Fig. 3 is a transverse section as on line *x*, Fig. 1, of a block laid in a wall; Fig. 4 is a face view of a portion of a wall showing a slightly modified construction of building block, said wall being partly pointed up; Fig. 5 is a sectional view, as on line *y*, Fig. 4, of said modified construction; Fig. 6 is an enlarged section showing a still further modification in detail, and Fig. 7 shows a building block of the first said modified construction adapted to be employed on a corner.

In said drawings, 1 indicates a building

block of my improved construction, said block being pressed or molded from concrete, cement, terra cotta or any other suitable or well-known material. Centrally the block is 60 hollowed, as at 2, to secure lightness as has been common, and obviously the block may be of any desired size or shape. The display face of the block or face adapted to be exposed in building is provided with inserts 65 which are of tile or any other suitable material and embedded in the said block. These inserts are one integral piece with the block as it is manufactured and supplied for building purposes, the said inserts being 70 preferably arranged in the bottom of the mold to receive the cement when poured thereon in molding a block, or under some conditions the inserts could be molded first in the bottom of the building-block mold by employing a false bottom, and when they have hardened sufficiently, removing the said false bottom and pouring or molding the main body of the building block. 75

In Figs. 1 to 3, inclusive, I have shown 80 inserts 3 embedded in the block body so that their faces will be flush with the surface of the cement body 4 of the block, the bottom and edge surfaces of each insert being directly in adhesive connection with the 85 cement or concrete forming the block, and held firmly thereby as an integral part of the block. Obviously by making the tile inserts about the size of a brick in their exposed surface, the effect of a brick wall may 90 be secured and the layers of cement between the inserts will represent the mortar courses in brick work. In carrying this out, said layers of cement may at their exposed edges be flush as shown, or may project, be recessed, or treated in any other manner to 95 secure a desired effect.

In Fig. 4, inserts 5 are shown as projecting from the face of a building block, and they may either be left this way, as shown 100 in Figs. 4 and 7, or the longitudinal spaces or channels 6 between the inserts may be pointed up or filled with mortar to conceal the fact, that the construction is of blocks, as at 11 in a portion of Fig. 4. To further 105 this construction, the end or ends of the block might be irregular so as to provide an interlocking of the tile inserts and secure the appearance of stretcher bond.

In Fig. 6 a construction similar to that of 110 Figs. 4 and 5 is shown, but the inserts 7 have curved or recessed edges 8 into which

the cement enters so as to absolutely prevent any possibility of the insert escaping from the block. These grooves may extend outward to the front or exposed face of the 5 insert, so that the projecting portion of the insert will have under-cut edges as at 9. The advantage of this is that in pointing up, the mortar is more firmly held in the grooves or recesses and is much less liable to deterioration or loosening by the weather.

Obviously where the longitudinal spaces between the inserts are to be pointed up or filled with mortar to hide the block construction, it is necessary that they be absolutely uniform. While this is easy enough 15 on the face of the block, it is not so readily obtained at the joining of contiguous blocks, and I have therefore provided for this purpose the construction shown and next to be 20 described. Upon each of two adjacent faces of the block, preferably the bottom and one end, are provided protuberances 10 which are formed or molded on the block and hence are uniform. Preferably these 25 protuberances are conical or tapering, so that when the blocks are laid the protuberances will push through the soft mortar or cement and engage the adjacent block, thus holding them at a fixed distance apart. Obviously, 30 any number of these protuberances may be employed, although for purposes of illustration I have shown three on each block surface. These protuberances 10 insure a uniform and exact thickness of the grouting or 35 mortar courses, but they are not sufficiently strong to take the strain or load after the wall is built, but would crush and permit the block to rest on its entire face; thus there is no cracking or impairing of a lower series 40 of blocks under the heavy lead of subsequent or upper series. Furthermore, the protuberances described are of use in shipping the building blocks loose, to hold them apart and prevent injury and damage to the sharp 45 edges by their coming in contact.

Obviously the inserts need not necessarily be in the representation of bricks, as I have shown in the drawings, but may be of other suitable forms, and various designs may be 50 worked out, either of the inserts alone or of the same in combination with exposed cement portions of the block, according as one's fancy or taste may dictate.

Having thus described the invention, 55 what I claim as new is:

I. A building block consisting of an integral body portion having laying faces and a display side adapted to be exposed, a plurality of inserts differing from said body 60 portion embedded in the said display side and separated by spaces, and protuberances upon one of said laying faces adapted to en-

gage another similar block and hold adjacent inserts on the two blocks at the same distance apart as are inserts on the same 65 block.

2. The combination of a series of building blocks each comprising a body portion having a laying face and a display face and inserts differing from said body portion permanently embedded in the said display face thereof and separated by intervening portions of said body portion, and means between the adjacent laying faces of two blocks holding them with adjacent inserts 70 on their display faces at substantially the same distance apart as are inserts on the same block.

3. The combination of a series of building blocks each comprising a body portion having a laying face and a display face and inserts differing from said body portion permanently embedded in the said display face thereof and separated by intervening portions of said body portion, means between 75 the adjacent laying faces of the two blocks positively holding them with adjacent inserts on their display faces at substantially the same distance apart as are inserts on the same block, and a filling of mortar or 80 the like between said adjacent laying faces 85 substantially flush with the fronts of the body portions of the blocks.

4. The combination of a series of building blocks each having a laying face and a display face with alternating projecting portions and depressed channels, means between the adjacent laying faces of two blocks holding them with adjacent projecting portions of their display faces at the same distance 90 apart as are projections on the same block, and a uniform filling of mortar or the like 95 extending between every two adjacent projecting portions throughout the series of blocks, whereby the joints of the blocks are 100 disguised.

5. A building block consisting of a body portion having laying faces and a display side, and a plurality of inserts differing from said body portion and having longitudinally recessed edges embedded in said display side of the body portion and projecting therefrom to expose a transverse part of said edge recess, adjacent inserts being separated by channels and portions of 110 the body portion which enter the embedded parts of the said edge recesses, and mortar 115 in said channels entering the said exposed parts of the said edge recesses.

FREDERIC W. MacQUESTEN.
